[57] **CLAIM**

The ornamental design for a lighter, as shown and described.

DESCRIPTION

FIG. 1 is a perspective view including the front, top and one side of a lighter showing our new design;

FIG. 2 is an elevational view of the lighter on an enlarged scale, taken from the side opposite that shown in FIG. 1;

FIG. 3 is a front elevational view thereof on an enlarged scale;

FIG. 4 is a rear elevational view thereof on an enlarged scale;

FIG. 5 is a top plan view thereof on an enlarged scale; and

FIG. 6 is a bottom plan view thereof on an enlarged scale.
